DESIGN FOR A COMPACT CASE

Mack M. Forman, Providence, R. I., assignor to Marathon Company, a corporation of Massachusetts

Application November 25, 1936, Serial No. 66,131

Term of patent 3½ years

To all whom it may concern:

Be it known that I, Mack M. Forman, a citizen of the United States of America, residing in Providence, county of Providence, State of Rhode Island, have invented a new, original, and ornamental Design for a Compact Case, of which the following is a specification, reference being had to the accompanying drawing forming a part thereof.

Fig. 1 is a plan view of a compact case embodying my new design;

Fig. 2 is an edge view; and
Fig. 3 is a side elevation thereof.

The dominant features of my design reside in the portions shown in full lines.

I claim:

The ornamental design for a compact case, substantially as shown and described.

MACK M. FORMAN.
